UNITED STATES PATENT OFFICE.

ALEC J. GERRARD AND PARVIN WRIGHT, OF CHICAGO, ILLINOIS.

COILED TIE WIRE.

Application filed June 14, 1922. Serial No. 568,304.

To all whom it may concern:

Be it known that we, ALEC J. GERRARD and PARVIN WRIGHT, respectively a subject of the King of Great Britain and a citizen 5 of the United States, each residing at Chicago, in the county of Cook and State of Illinois, have invented certain new and useful Improvements in Coiled Tie Wires; and we do hereby declare the following to be a 10 full, clear, and exact description of the invention, such as will enable others skilled in the art to which it appertains to make and use the same.

This invention relates to bale ties or tie 15 wires provided with deformed ends, and has for its object to provide such wires in the forms of coils, to the end that the user may cut off convenient lengths at will.

With these and other objects in view the 20 invention consists in the novel details of construction and combinations of parts more fully hereinafter disclosed and particularly pointed out in the claims.

Referring to the accompanying drawings 25 forming a part of this specification, in which like numerals designate like parts in all the views:—

Figure 1 is a diagrammatic view of a wire 30 coil made in accordance with this invention; Figure 2 is a view similar to Figure 1, of a somewhat modified form of wire;

Figure 3 is a side elevational view of a 35 wire holding post adapted to hold the tie wires of Figures 1 and 2 when they are used in a machine;

Figure 4 is an end elevational view of the 40 parts shown in Figure 3;

Figure 5 is a view similar to Figure 1, but showing a still further modified form of wire 45 making up the coil;

Figure 6 is a side elevational view of a modified form of wire holding post adapted to receive the wire shown in Figure 5; and

Figure 7 is an end elevational view of the 50 post shown in Figure 6.

In order that this invention may be the more clearly understood it is said: In our 55 pending application Sr. No. 541777, filed March 7, 1922, and entitled Tensioning and twisting machines, there is described a type of machine for using wires of the character made the subject of this application, and which machines are provided with posts such as those illustrated in Figures 3, 4, 6 and 7, 60 to hold the wires.

The ends of the wires are held in said

posts whereupon their bights are passed around the package, two parallel bights are placed under tension by the machine, are twisted together, and the wire is severed, 60 whereupon the package is firmly bound. These wires are ordinarily cut off into fixed lengths and sold to the users of the machine. On the other hand, it often happens that the particular length of wire selected is too short 65 or too long for the package, and therefore, it is desirable to have these wires in coils so that the user may select a length of wire which is suitable for the particular box or package he is to band. On the other hand, 70 as will be clear from Figures 3 and 4, the holding posts 1 of the above mentioned machines are provided with slots 2 to receive the flattened portions 3 of the wires 4, and it is very desirable that these flattened portions should occur at convenient distances apart so that when a given length of wire is drawn from the coil no substantial waste of 75 the wire will occur.

Therefore, according to this invention, we 80 provide a coil of wire 5 made up of a continuous strand of wire 6, having say every five or six inches of its length or at some other convenient distance, the flattened or deformed portions 7. It thus results that 85 the user of these coils of bale ties may draw out the wire 6 for a length which will encircle the package to be wired, and to then stop the length drawn out at the convenient notch 7 which will make his wire slightly 90 longer than the girth of the box. He then severs the wire and uses it in the machine in the ordinary manner.

It should be stated that when this length of wire is thus cut from the coil 5, and its 95 deformed end 8, (see Fig. 4), is placed in the post 1, and tension brought thereon, its end is turned down, as illustrated, which in the finished knot prevents said end 8 from sticking up and tearing the hands of the 100 operator or tearing packages that may be moved over the knot.

In the somewhat modified form of the invention illustrated in Figure 2, the coil 9 of wire is the same as that shown in Figure 105 1, except the depressed notches or deformations 7 are placed a distance apart equal to the average girth of the average box to be banded. That is, the distance between the notches 7, in Figure 2, is the same as 110 the length of the tie wires now commonly sold on the market for these machines, which

- is about 10 feet. Coils of wire 9 of this character are especially adapted for use in department stores, packing houses, etc., where the boxes are of substantially the same size, but they are not adapted for use in small grocery stores and in other places where there will be a variation in the size of the package to be wired, because, an excessive waste would be encountered.
- 10 In the coils 5 and 9 the cross section of the wire is changed by the notches 7. On the other hand, in the still further modified form of coil illustrated in Figure 5, the cross section of the wire is not changed.
- 15 The deformed portions 10 are made by merely corrugating the wire 6 at predetermined intervals. This particular form of deformation is especially adapted for the form of wire holding post 11 which is provided
- 20 with a corrugated slot 12, as illustrated, and which slot is of the proper size and shape to fit the corrugated portions 10 of the wire 6. The wire 6 having been thus corrugated, it is wound up into a coil 15
- 25 from which the wire is drawn in suitable lengths for use in the machine, in the manner above disclosed.

What we claim is:—

1. The herein described new article of manufacture consisting of a coil of wire 30 adapted for use in wire tying machines and provided with deformed integral portions adapted to fit said machines at predetermined intervals in its length, substantially as described. 35

2. The herein described new article of manufacture consisting of a coil of wire adapted for use in wire tying machines and provided at predetermined intervals with deformed integral portions of a less cross 40 section than the main body portion of the wire, substantially as described. 40

3. The herein described new article of manufacture consisting of a coil of wire adapted for use in wire tying machines and 45 provided with deformed integral portions at intervals whose distance apart is less than the circumference of the package to be wired, substantially as described.

In testimony whereof we affix our signatures. 50

ALEC J. GERRARD.
PARVIN WRIGHT.
